UNITED STATES PATENT OFFICE.

ORREN A. SAWYER, OF LOWELL, MASSACHUSETTS, ASSIGNOR TO EARL A. THISSELL, OF LOWELL, MASSACHUSETTS.

HARNESS-LOOSENER OF LOOMS.

No. 871,096.

Specification of Letters Patent.

Patented Nov. 12, 1907.

Application filed December 28, 1906. Serial No. 349,873.

To all whom it may concern:

Be it known that I, ORREN A. SAWYER, a citizen of the United States, residing at Lowell, in the county of Middlesex and Commonwealth of Massachusetts, have 5 invented a certain new and useful Improvement in Harness-Looseners of Looms, of which the following is a specification.

This invention relates to harness-looseners of looms and has for its object to furnish a means for slackening the 10 harnesses and the warp-threads of a loom to facilitate the drawing in of broken warp-threads, the mending of broken harness-eyes, the attachment of jacks, and the adjustment of harness-cams by the loom-fixer.

Said invention also lessens or obviates the danger of 15 breaking other warp-threads in the operation of mending previously broken threads, the liability, in putting up, taking down or adjusting the harnesses, of pulling out the screw-eyes by which the jacks and harness-stands are connected to the harness-shafts, and of making 20 thick and thin places in the cloth.

The more numerous the harnesses are, the more useful the invention hereinafter described.

In weaving, the heddles are drawn taut by the strapping which connects the harnesses to the saddle-roll 25 above and to the treadles below and the warp-yarns are also strained between the whip-roll and the fell or making edge of the cloth, so that in mending broken yarns it is necessary to part the heddles nearest the operator 30 to reach the heddles behind or in front, usually in front, because the broken ends are usually drawn forward through the heddles and reed. In parting or pushing aside the heddles, the warp-threads carried thereby are liable to be broken and one hand of the operator and considerable muscular force is required to hold the heddles 35 out of the way. Frequently, the operator swings the lay forward to increase the space between the lay and the harnesses and to reach the latter over the top of the former. Swinging the lay forward is likely to loosen the warp-threads by drawing from the warp-beam so that a "thin place" will be formed when the 40 loom is subsequently started, because when the warp is loosened by turning the warp-beam, said beam would only with great difficulty be replaced or turned back to its former position.

45 In the accompanying drawing, on three sheets, Figure 1, is a side elevation of my invention with such parts of a loom as are necessary to the understanding of said invention, showing the harnesses and warp-threads in normal position; Fig. 2, a similar view showing said 50 harnesses and warp-threads slackened; Fig. 3, a front elevation of a part of a loom frame, with a reed, and harnesses and connected parts, and with my improvement.

A denotes a loom-frame having an arch *a*; B, breast-beam; C, a lay-beam; D, a reed; E, a drop-wire; F,

a warp-beam; these parts being all of any usual construction.

The harnesses *F¹ F² F³ F⁴* are of ordinary construction and each consists of two parallel harness-shafts *f⁰, f* connected by flexible heddles *f¹⁶*. These harnesses are 60 connected in pairs by harness-roll straps *f¹ f²*, which pass over harness-rolls *f³ f⁴* and each end of each harness-roll is supported by a saddle-roll strap *f⁵ f⁶*, said straps *f⁵ f⁶* being secured to rolls or bosses *f⁷ f⁸* on the saddle-roll *f¹⁵*. The lower edges or lower harness shafts of the 65 harnesses are connected to jacks *f⁹ f¹⁰* by jack-straps *f¹¹ f¹²* which in turn are connected to the treadles (not shown) in the usual manner, said treadles being depressed by cams on the cam-shaft (neither being shown) in a well understood manner. 70

It will be understood that the straps *f¹ f² f¹¹ f¹²* are connected to the harness-shafts not directly but through the medium of screw-eyes *f¹³* and hooks *f¹⁴*.

The saddle roll *f¹⁵* is journaled upon stands mounted upon the arch *a* of the loom frame. Each of these stands 75 is usually formed in one piece. I support the saddle-roll in a somewhat similar manner but I make each stand in two parts, a stationary part *G¹ G²* (secured to the arch *a* in any usual manner) and an upper part *G³ G⁴*, jointed to the lower part by means of a shaft *G* 80 which turns freely in both of the lower stand parts *G¹ G²* but to which both of the upper parts *G³ G⁴* are rigidly secured, as by radial set-screws *g¹ g²*.

The two parts of each stand are shown in their normal relative position in Fig. 1, the upper and lower stand 85 parts having flat contacting stop-surfaces, indicated by the dotted straight line *g*, which limit the backward movement of the upper stand part upon the lower. In the other direction, the movement of the upper part of each stand is limited by said upper part striking on said 90 stop surface *g* of the lower part.

The shaft *G* is rocked to depress the saddle-roll *f¹⁵* and bring it nearer the jacks *f⁹ f¹⁰*, that is, to slacken the parts including the heddles which are stretched between said jacks and saddle-roll, thus leaving the heddles and warp-threads free to be moved laterally or up and down without strain or danger of being broken. 95

I have shown a lever or handspike *H* arranged to slide radially in the shaft *G* by which said shaft may easily be turned by hand in either direction. This 100 lever *H* is provided at one end with an enlargement *h* and at the other with a hole which receives a cotter-pin *h¹*, said enlargement and pin preventing the removal of said lever from said shaft *G* and said enlargement *h* serving as a handle. Said handspike may be 105 shoved back when the harnesses are loosened to be out of the way of the operator when piecing up.

I claim as my invention:—

1. The combination in a loom, of harnesses, each comprising an upper and a lower harness-shaft and flexible 110

- heddles connecting said shafts, a saddle-roll, flexible connections between said saddle-roll and each of said harnesses and means of supporting and raising or lowering said saddle-roll, to tighten or loosen said harnesses.
- 5 2. The combination in a loom, of a frame, stands, each formed in two parts, one of which parts is stationary on said frame and the other of which parts is movable in said stationary part, said movable parts being rigidly connected to each other, a saddle-roll supported on said movable parts, harnesses, each comprising an upper and a lower harness-shaft and flexible heddles connecting said shafts, and flexible connections between said harnesses and said saddle-roll, to vary the tension of said connections and harnesses by changing the position of said saddle-roll.
- 10 3. The combination in a loom, of a frame, stands, each formed in two parts, one of which is stationary on said frame, a shaft journaled in said stationary parts, the other parts of said stands being rigidly secured to said shafts, a saddle-roll journaled in said last named stand-parts, harnesses, each comprising an upper and a lower harness-shaft and flexible heddles connecting said shaft, and flexible connections between said harnesses and said saddle-roll, to vary the tension of said harnesses by the turning of said shaft.
- 15 4. In a loom, the combination with the harnesses and
- the flexible harness-connections by which the said harnesses are caused to move reciprocally with relation to each other, of a saddle-roll with which the said harness-connections are connected, and which is held in the normal or working position thereof, with the harness-connections 30 taut, by the strain applied through the said harness-connections, and adapted to be shifted from such position into a position to loosen the harnesses.
5. In a loom, the combination with the harnesses, the flexible harness-connections by which the said harnesses 35 are caused to move reciprocally with relation to each other, and a saddle-roll with which the said harness-connections are connected, of a pivotally-mounted support for the said saddle-roll having a normal working position in which it is held by the strain applied through the said harness-connections acting effectively at one side of the pivotal axis, and movable to the other side of the said axis to thereby relax the harness-connections and loosen the harnesses.
- 40 In witness whereof, I have affixed my signature, in presence of two witnesses.
- 45 ORREN A. SAWYER.
